UNITED STATES PATENT OFFICE.

DAVID L. RANLETT, OF NEW YORK, N. Y., ASSIGNOR TO AMERICAN BALSA COMPANY, INC., A CORPORATION OF NEW YORK.

DESIGN FOR A SURF-BOARD.

55,079.

Specification for Design.

Patented May 4, 1920.

Application filed November 28, 1919. Serial No. 341,329. Term of patent 7 years.

To all whom it may concern:

Be it known that I, DAVID L. RANLETT, a citizen of the United States, residing at the borough of Manhattan, city, county, and State of New York, have invented a new, original, and ornamental Design for a Surf-Board, of which the following is a specification, reference being had to the accompanying drawing, forming a part thereof.

Figure 1 is a plan view of a surf board embodying my invention;

Fig. 2 is a side elevation of said board; and

Fig. 3 is a view of the front end of said surf board.

I claim:

The ornamental design for a surf board, as shown.

DAVID L. RANLETT.
